FLUID CONTROL SYSTEM

William V. Sauter and Howard F. Lawrence,
Philadelphia, Pa., assignors to American En-
gineering Company, Philadelphia, Pa., a cor-
poration of Pennsylvania

Application May 18, 1935, Serial No. 22,217

15 Claims. (Cl. 110—44)

This invention relates to fluid control systems, and more particularly to systems employed to control the flow of draft air to stoker furnaces.

It is the primary object of the present invention to provide a generally improved fluid control system for stoker furnaces which prevents an excess of air from flowing through the tuyères thereof upon a reduction in the fuel bed resistance.

Another object is to provide a fluid control system for stoker furnaces which improves the distribution of air to the fuel bed whereby the latter is maintained normally uniform under all conditions of operation.

A further object is to provide each stoker tuyère with independent means for controlling the flow of air therethrough.

A further object is to provide each tuyère of a stoker with an independent air control device which occupies a minimum of space and which requires a minimum of work to install.

A still further object is to provide each tuyère with an independent air control device which is self adjusting and which requires no field attention.

A still further object is to provide a simplified control device for regulating the flow of air through the tuyère blocks of a stoker furnace, which is highly efficient in operation, as well as economical to manufacture.

Other and further objects will become apparent as the description of the invention progresses.

Of the drawings, Fig. 1 is a longitudinal sectional view taken through one of the retorts of a stoker furnace.

Fig. 2 is a side elevational view partly in section and diagrammatic in part, of a series of tuyère blocks showing one form of air regulating device associated therewith.

Fig. 3 is a perspective view of one of the tuyère blocks shown in Fig. 2 with a portion thereof broken away to show the arrangement of the control device associated therewith.

Fig. 4 is a plan view of a tuyère block in inverted position with the control device separated therefrom.

Fig. 4^a is an enlarged elevational view of the damper unit shown in Figs. 2 to 4.

Fig. 5 is a side view partly in section of a plurality of tuyère blocks showing a modified type of air control mechanism therefor.

Fig. 5^a is an enlarged sectional view of one of the dampers shown in Fig. 5.

Fig. 6 is a view similar to Fig. 5 but showing the air control devices in operated position.

Fig. 7 is a plan view of one of the tuyère blocks shown in Figs. 5 and 6 in inverted position, with the associated air control device separated therefrom.

Fig. 8 is a plan view of a tuyère block in inverted position showing a still further type of air control device associated therewith.

Fig. 9 is a sectional elevational view of a series of tuyère blocks of the type shown in Fig. 8.

The present invention, for the purpose of illustration, is shown applied to a stoker of the underfeed type, although it is apparent that the invention is equally applicable to other types of stokers, as well as other apparatus wherein control of a fluid is desired. As illustrated in the drawings, each tuyère is provided with a damper. In some instances the damper controlling the air flow to one tuyère overlaps with the damper controlling the air flow to an adjacent tuyère, and thus these overlapping dampers form communicating passages to the tuyères. In cases where the area of each of these communicating passages is substantially the same as the area of the tuyère openings the pressure of the air therein is substantially the same as that flowing through the tuyères. Air is supplied to each of the tuyères from a common pressure or plenum chamber wherein the pressure remains substantially constant during operating periods of the furnace at any given rating. It therefore will be observed that should the fuel bed over any of the tuyères develop a blow hole, or become abnormally porous, so as to cause the velocity of the air supplied thereto to increase, while the fuel bed over an adjacent tuyère block remains normal, thereby imposing the normal resistance to the air flowing thereto, the damper associated with the first tuyère will be subjected to a greater pressure at one side than at the other, and obviously will tend to move in the direction of the lesser pressure. As the velocity of the air past a damper increases the static pressure decreases, and as a result the damper will be urged to closed position to throttle the air supply to the abnormally thin or porous portion of the fuel bed. Therefore, by this arrangement of overlapping dampers the flow of air through one tuyère is controlled, to a certain extent, by the flow of air through an adjacent tuyère.

The drawings also illustrate various arrangements of dampers wherein the flow of air to each tuyère is independently controlled. In these arrangements one surface of each damper communicates with a passage leading to an associated tuyère, while the other surface thereof

communicates with the plenum or air supply chamber. Inasmuch as the plenum chamber pressure is always greater than the static pressure of the air in the restricted passage of the 5 tuyères the dampers will be subjected to a differential pressure. In such constructions the dampers may be provided with weights or be constructed of relatively heavy material so that they will remain open until a predetermined differential pressure is imposed thereon, at which 10 time they will move toward closed position.

It therefore is seen that should thin or extremely porous spots develop in the fuel bed the damper or dampers controlling the air thereto 15 will close. The fuel feeding elements will then have the opportunity of build up such thin portions of the fuel bed before damage can occur to the underlying grates. As the fuel bed builds up, and therefore offers a greater resistance to 20 the flow of air through the associated tuyères, the differential pressure acting upon the damper or dampers controlling the air thereto will be reduced, and as a result they will move toward open position and again permit a normal quantity 25 of air to flow to those portions of the fuel bed. The dampers, therefore, tend to maintain the fuel bed normally uniform throughout and thus prevent blowing of the fuel, as well as damage 30 to the grates, in the event abnormally thin spots occur therein.

Referring to the drawings, the numeral 1 designates a stoker of the underfeed type having alternately disposed retorts 2 and tuyère rows 3. Fuel is supplied to retorts 2 from a hopper 4, 35 and any suitable feeding device driven by a power mechanism indicated at 5 feeds the fuel gravitating in hopper 4 to the retorts 2. A series of pushers 6 mounted in the bottom of each retort 2 is also operated by the power mechanism 40 5 through the connections 7. These pushers underfeed the fuel along the retorts and tuyères to an extension grate 8, which in turn overfeeds the fuel to an ash pocket 9 disposed at the rear of the stoker. It is to be understood that the 45 invention hereinafter described is not to be limited to its application to underfeed stokers, since it is equally adaptable for use in connection with other types of stokers, as well as other apparatus wherein flow control is desired.

50 When the terms "front" and "rear" are hereinafter used in connection with the description of the elements of the stoker 1 and the associated fluid control, it will be understood that the portions of such parts extending toward the rear 55 or ash pocket 9 of the stoker will be designated as "rear", and those portions thereof extending toward the front or the driving mechanism 5 of the stoker will be designated as "front".

Referring more particularly to Figs. 1 to 4 inclusive, which constitute the preferred embodiment of the present invention, each tuyère row 3 comprises a series of superimposed tuyère blocks 10 each having a rounded nose or rear portion 11, and a substantially rectangular front portion 12. 65 The upper surface 13 of each tuyère block is substantially flat and has a slightly beveled portion 14 extending around the nose portion thereof. The under side of each tuyère block is provided with a series of relatively long and relatively 70 short ribs 15 and 16 respectively, which diverge from front to rear of the tuyère block, as shown in Fig. 4, on either side of a longitudinally extending dividing rib 17. A pair of spaced rearwardly diverging ribs 18 are also provided on the 75 under side of each tuyère block which in the

present instance define an inlet passage 19 for draft air. Ribs 18 terminate at the rear ends thereof in extended flat supporting portions 20. Each tuyère block has also provided on the under side thereof a pair of inclined supporting surfaces 5 21 which in assembly seat upon the side plates 22 of adjacent retorts 2. The under side of each tuyère block is also provided with a pair of widely spaced locking lugs 23 which in assembly engage in the substantially rectangular openings 10 or apertures 24 of the next lower tuyère block of the series. Ribs 18 extend forwardly of the front edge 25 of each tuyère block and are provided with a pair of aligned apertures 26 disposed near the lower forward ends thereof. Draft air enters the tuyères from a common pressure or plenum chamber 27 disposed beneath the stoker which in turn is supplied with air from any suitable fan mechanism (not shown) in a well known manner.

Upon reference to Figs. 2 and 3 it will be noted that an air control unit, designated generally at 30, is provided for each of the tuyère blocks 10. Control device 30 comprises a pair of pivotally mounted damper elements 31 and 32 respectively which extend between ribs 18, and which are connected for simultaneous movement by a link 33 of any suitable construction. Damper element 31 comprises a relatively flat portion 34 terminating at its rearwardly disposed end in an arcuate 30 portion 35. The arcuate portion 35 makes an angle of substantially 90 degrees with the flat portion 34 and the rear surface of the former engages or is slightly spaced from the front edge 25 of its associated tuyère block 10. The front 35 end of each damper element 31 is provided with a pair of depending apertured ears 36 the apertures of which in assembly align with the apertures 26 provided at the forward ends of ribs 18 and a pair of pins 37 pivotally secure damper 40 elements 31 to the ribs 18. Damper elements 32 are also pivotally supported in any suitable manner to ribs 18 of their respective tuyère blocks, such as by a pair of pins 38. It therefore is seen that the upper surface of a damper element 31, 45 mounted on one tuyère block 10, forms with the damper element 32 of the next higher tuyère block and ribs 18 a passage 40 which communicates with the inlet passage 19 between those tuyère blocks. By this construction all of the air 50 entering the tuyère blocks must pass through an associated pair of damper elements 31 and 32 and thence to inlet passage 19 before it may enter the fuel bed.

Referring more particularly to Fig. 2, it will 55 be observed that the lower surfaces of damper elements 31 and the upper surfaces of elements 32 are subjected to the pressure in plenum chamber 27. However, since the areas of these surfaces are substantially the same, it is apparent 60 that no movement will be imparted to said elements by this pressure. It will also be observed that the upper surface of each damper element 31 extends forwardly from the upper surface of an associated tuyère block which constitutes the 65 bottom wall of an inlet chamber 19, while the lower surface of the damper element 32 extends forwardly of the lower surface of the tuyère block, which constitutes the upper wall of the next lower inlet chamber 19. It is also seen that inasmuch as the elements 31 and 32 of each unit are interconnected by an element 33, any movement imparted to one of said elements is also imparted to the other. Therefore, should the 70 velocity of the air in one chamber 19 increase, 75

thereby reducing the static pressure operating against the upper surface of the associated damper element 31, while the velocity of the air in the next lower chamber 19 remains substantially the same, thereby imposing the normal pressure against the lower surface of damper element 32 for that unit, it will be readily seen that since the pressure acting against the lower surface of element 32 is greater than the pressure 5 acting against the upper surface of the upper element 31, both of said elements of the unit will tend to move upwardly. These damper elements may be so designed that the dead weight thereof will be sufficient to hold them open for a predetermined differential pressure or have weights or 10 springs associated therewith for that purpose. When this differential pressure increases due to a decrease in fuel bed resistance, the damper element 31 will move upwardly into engagement 15 with damper element 32 of the next higher tuyère block of the series thereby throttling the flow of air therethrough. When the damper elements have thus been actuated to closed position a slight leakage of air occurs past the contacting 20 surfaces thereof. As a result the damper elements are subjected to a differential pressure of sufficient intensity to maintain them in closed position. If no leakage occurred under these 25 conditions damper elements 31 would drop slightly from their fully closed positions and would then be instantly actuated to closed position again. This action would be repeated until the fuel bed overlying the associated tuyère blocks imposed a greater resistance to the flow of air, 30 and the weight of the dampers would be sufficient to overcome the resulting change in differential pressure. In either case the air flow to the thin or porous portions of the fuel bed is throttled sufficiently to prevent blow holes or 35 damage to the tuyère blocks. Thus when the air is so throttled the combustion rate will decrease, thereby enabling the fuel feeding elements to build up that portion of the fuel bed until it becomes normally uniform again. This 40 change in fuel bed density creates a greater resistance to the flow of air which causes the pressure of the air in the associated passage 19 to increase, thereby decreasing the differential in 45 pressure acting on the associated damper elements, and as a result the damper elements will move downwardly toward open position to permit more air to flow through the associated tuyère. Referring to Fig. 2, the damper elements shown at A, B and C are in operated position, 50 thereby shutting off the flow of air to the associated tuyère blocks. The arcuate portions 35 act as seals to prevent leakage of fluid past the dampers when the latter are in closed position. It therefore is apparent that the damper elements 55 31 and 32 associated with the tuyère blocks beneath the lighter portions of the fuel bed are operated automatically to close or partially close the passages 19 thereof, while those associated with tuyère blocks beneath the heavier portions 60 of the fuel bed will remain open to permit a greater quantity of air to flow therethrough, and as a result proper distribution of air to all portions of the fuel bed is assured for all conditions of operation. 65

Figs. 5 to 7 show a somewhat simplified embodiment of the present invention, wherein each tuyère block 42 has attached thereto a single damper element 43. In this construction each tuyère block 42 has provided at the front end 70 thereof a substantially rectangular recess 44 in

which is mounted the damper 43. As will be seen upon reference to Fig. 7, damper 43 occupies substantially the entire recess 44, and is of box-like construction having substantially flat top and bottom surfaces 45 and 46 respectively terminating at the rear ends thereof in a vertically disposed arcuate portion 47 which abuts or is slightly spaced from the rear wall 49 of recess 44. The forward ends of top and bottom surfaces 45 and 46 terminate in a rounded portion 10 50 having projecting rearwardly from the opposite sides thereof a pair of apertured ears 51 and 52. A pair of forwardly extending projections 53 and 54 which form a portion of the side walls of recess 44 are each provided with a transverse aperture 55 which, when the damper 43 is assembled on the tuyère block 42, align with the apertures provided in ears 51 and 52 respectively, and pin 56 inserted through these apertures pivotally supports the damper on said 15 tuyère block. As shown more particularly in Figs. 5 and 6, the under side of each tuyère block 42 is provided with a depending projection 48 which partially closes the inlet opening between adjacent tuyère blocks. This projection is provided simply for the purpose of reducing the travel of damper elements 43 and may be eliminated if desired. Fig. 5 shows the parts in normal position wherein it will be noted that each of the dampers 44 rests upon a pin 57 to limit 20 the downward movement thereof. In this construction each damper 43 forms with the under side of the next upper tuyère block of the series a passage 58 which communicates with the inlet passage 19' defined by adjacent tuyère blocks and 25 ribs 18', and accordingly the upper side thereof is exposed to the pressure of the air in said passage. The lower surface of damper 43 is at all times exposed to the pressure in the plenum chamber, and consequently when any flow exists through the tuyère block each damper will be subjected to a differential pressure. In this case also the dampers 43 may be so constructed that their dead weight is sufficient to maintain 30 the same in open position for a predetermined 35 differential pressure or each may have a weight W provided at the rear end thereof. 40

Thus, in the event the resistance to the flow of air through the tuyère blocks should decrease, thereby increasing the velocity of the flow therethrough, the static pressure operating against the upper surface of the damper elements will be reduced. Inasmuch as the lower surface of each of these dampers is subjected to plenum chamber pressure which remains constant for 50 any given fuel burning rate and which is always greater than the static pressure acting against the upper surface of the damper, each of the dampers is subjected to a differential pressure. When this differential pressure is sufficient to 55 overcome the weight of the dampers, the latter will move upwardly into engagement with the projections 48, as shown in Fig. 6, thereby cutting off the flow of air through the associated tuyère blocks, and as a result the air supply to the portions of the fuel bed above such tuyère blocks will be reduced. The fuel feeding mechanism may then build up such thin spots before any damage occurs to the underlying stoker parts. In this construction also a slight leakage occurs 60 past the dampers when in closed position, and consequently they are subjected to a differential pressure of sufficient intensity to retain them 65 in closed position. 70

A still further modification of the present in- 75

vention is shown in Figs. 8 and 9. In this construction a pair of damper elements 76 and 77 are provided for each tuyère block 78. By this arrangement a somewhat better distribution of the air may be obtained inasmuch as it sometimes occurs that the density of the fuel bed over one side of a tuyère block is greater than that over the other, and when such a condition occurs damper element 76 or 77 may move to closed position, while the other remains open. Damper elements 76 and 77 operate in the substantially rectangular recesses 79 and 80 respectively, provided at the front end of the tuyère block. These dampers each comprises a substantially flat portion 81 which terminates in a vertically disposed arcuate portion 82 which engages or is slightly spaced from the rear wall 83 of the recess 79 or 80. Each of these dampers also has provided at the front end thereof a pair of apertured ears 84, the apertures therein in assembly align with apertures 85 provided in the forwardly extending projections 86, 87 and 88 respectively, of tuyère block 78, and a pin 89 extending through these apertures pivotally supports the dampers in position. The operation of dampers 76 and 77 is similar to that of dampers 43 and 62 previously described.

In all of the embodiments of the invention herein described, it will be observed that the dampers are disposed substantially longitudinally in respect to the direction of air flow to the tuyère blocks. Thus, the impact head of the air flowing past the dampers has little or no effect on the operation thereof.

The various novel forms of air control devices hereinbefore described obviously are not only simple in construction, but are highly efficient in operation. The control dampers may be readily assembled on the tuyère blocks, and when assembled require no field adjustments or periodic attention by the operator of the stokers. Moreover, by employing the present invention the maintenance cost of the stoker is materially reduced inasmuch as an independent damper is provided for controlling the draft air passing through each tuyère block which operates automatically as soon as the fuel bed resistance decreases to a dangerous extent to shut off the air supply thereto, and thus immediately reduce the combustion rate at that point. The fuel feeding elements may then feed additional fuel to that portion of the fuel bed before the incandescent fuel has had the opportunity to cause any serious damage to the tuyère blocks. Blow holes which often occur in furnaces, especially in those employing forced draft, are practically eliminated by the use of the present invention.

Applicants have also provided control units which may be readily applied to stokers now in the field, as well as to new installations, without necessitating any changes to the structure thereof.

While the embodiments herein shown and described are admirably adapted to fulfill the objects primarily stated, it is to be understood that it is not intended to limit the invention to these embodiments since it may be embodied in other forms, all coming within the scope of claims which follow.

What is claimed is:

1. In a device of the class described, the combination of a tuyère block comprising a substantially flat body portion, a pair of spaced ribs depending from the under side of said body portion defining an inlet passage for draft air, a series of spaced ribs disposed between said first

mentioned ribs subdividing said passage into a series of smaller passages, and a pair of interconnected damper elements pivotally supported on said first mentioned ribs.

2. In a device of the class described, the combination with a series including tuyère blocks, of means disposed between said tuyère blocks defining passages for draft air, of a source of air supply communicating with said passages, an upper and a lower damper element pivotally mounted on each of said tuyère blocks adjacent the inlet to the associated of said passages, said damper elements being so disposed that when the static pressure in one passage falls below that in the next lower passage, the upper of said damper elements of one tuyère block will move into engagement with the lower damper element of the next adjacent tuyère block, thereby throttling the flow of air through the associated passage.

3. In a device of the class described, the combination of a tuyère block, comprising a substantially flat body portion, said body portion having an open substantially rectangular recess extending rearwardly from the front edge thereof, a damper mounted in said recess, said damper comprising substantially flat spaced upper and lower surfaces and a substantially arcuate end portion, said end portion being in substantial engagement with the rear wall of said recess, and means for pivotally supporting said damper on said tuyère block.

4. In a device of the class described, the combination of a tuyère block, comprising a substantially flat body portion, a pair of spaced ribs depending from the under side of said body portion defining an inlet passage for draft air, said body portion having an open substantially rectangular recess provided at the front end thereof and disposed between said ribs, a damper mounted in said recess and adapted to close said passage, and means for pivotally connecting said damper to said ribs.

5. In a device of the class described, the combination of a series of tuyère blocks, a pair of spaced ribs provided on each tuyère block defining with the adjacent tuyère block a passage for draft air, each of said tuyère blocks having an open substantially rectangular recess provided at the front end thereof, a damper mounted in each of said recesses and adapted to close said passages, means for pivotally connecting said dampers to said ribs, each of said dampers comprising a substantially flat portion extending longitudinally of said tuyère block and an end portion disposed at substantially right angles to said flat portion and adapted in assembly to lie in substantial engagement with the rear wall of said recess.

6. In a device of the class described, the combination of a tuyère block comprising, a body portion, means provided on said body portion defining passages for draft air, each of said passages being restricted at the inlet end thereof, and diverging toward its discharge end whereby the velocity of the air at the discharge end is relatively low, and automatic damper means mounted adjacent said tuyère block tending to close the inlet to said passages when the velocity of the air passing therethrough exceeds a predetermined value.

7. In a device of the class described, the combination of a tuyère block, means provided on said tuyère block defining one or more passages for draft air, an automatically operable damper

5 mounted adjacent each of said passages, each of said dampers comprising a relatively flat portion extending substantially longitudinally in respect to the direction of air flow to said passages, and an arcuate sealing portion disposed at an angle to said flat portion, and means for pivotally supporting said dampers.

8. In a device of the class described, the combination of a tuyère block, means provided on 10 said tuyère block defining one or more inlet passages for draft air, a source of air supply, a damper mounted adjacent each of said passages for controlling the flow of air thereto from said source of supply, each of said dampers comprising 15 a relatively flat portion, one side of which being subjected to the pressure of the air in its associated passage and the other side thereof being subjected to the pressure at said source of supply, whereby when said differential pressure exceeds 20 a predetermined value said damper is actuated thereby toward closed position, and sealing means provided on said dampers for preventing air leakage from said source of supply to said passages.

25 9. In a device of the class described, the combination of a series of tuyère blocks, means disposed between said tuyère blocks defining passages for draft air, a source of air supply, a damper mounted adjacent each of said passages 30 for controlling the flow of air thereto from said source of supply, each of said dampers comprising a relatively flat portion, one side of which being subjected to the pressure of the air in its associated passage, and the other side thereof 35 being subjected to the pressure at said source of supply, whereby when said differential pressure exceeds a predetermined value said dampers are actuated thereby toward closed position, and sealing means provided on said dampers for preventing air leakage from said source of supply 40 to said passages.

10. In a device of the class described, the combination of a series of tuyère blocks, means disposed between said tuyère blocks defining 45 passages for draft air, a source of air supply, a damper pivotally mounted on each of said tuyère blocks adjacent each of said passages for controlling the flow of air thereto from said source of supply, each of said dampers comprising a 50 relatively flat portion, one side of which being subjected to the pressure of the air in its associated passage, and the other side thereof being subjected to the pressure at said source of supply, whereby when said differential pressure exceeds 55 a predetermined value said dampers are actuated thereby toward closed position, and sealing means provided on said dampers for preventing air leakage from said source of supply to said passages.

60 11. In a device of the class described, the combination with a series of tuyère blocks, including means disposed between said tuyère blocks defining 65 passages for draft air, of a source of air supply communicating with said passages, and a damper unit mounted on each of said tuyère blocks, each of said damper units comprising a 70 pair of interconnected damper elements, one of the elements of each of said units lying adjacent the inlet passage to one of said tuyère blocks, while the other of said elements lying adjacent the inlet passage of an adjacent tuyère block, whereby each of said damper units is subjected to a differential pressure, and one of the ele-

ments of each of said units being adapted to automatically move into engagement with the other of the elements of an adjacent unit when the differential pressure to which said unit is subjected exceeds a predetermined value to 5 thereby throttle the flow of air to the said passage or passages of lesser pressure.

12. In a device of the class described, the combination of a tuyère block, means provided on 10 said tuyère block defining an inlet passage for draft air, a source of air supply, and an automatically operable damper mounted adjacent said passage for controlling the flow of air therein, said damper being disposed substantially longitudinally in respect to the direction of air 15 flow in said passage and being so arranged that one side thereof is subjected to the pressure of the air in said passages, and its other side to the pressure of the air at said source of supply, whereby when said differential pressure exceeds 20 a predetermined value said damper moves to closed position.

13. In a device of the class described, the combination of a tuyère block, means provided on 25 said tuyère block defining an inlet passage for draft air, a source of air supply, and an automatically operable damper pivotally mounted on said tuyère block for controlling the flow of air in said passage, said damper being disposed substantially longitudinally in respect to the direction of air flow in said passage and being so arranged 30 that one side thereof is subjected to the pressure of the air in said passage, and its other side to the pressure of the air at said source of supply, whereby when said differential pressure exceeds 35 a predetermined value said damper moves to closed position.

14. In a device of the class described, the combination of a plurality of tuyère blocks, means provided between said tuyère blocks defining inlet 40 passages for draft air, a source of air supply, and a plurality of automatically operable dampers, one damper being mounted adjacent each of said passages for controlling the flow of air thereto, said dampers being disposed substantially longitudinally in respect to the direction of air flow in said passages, and being so arranged 45 that one side of each is subjected to the pressure of the air in its passage and the other side to the pressure of the air at said source of supply, whereby when said differential pressures exceed 50 a predetermined value said dampers move to closed position.

15. In a device of the class described, the combination of a plurality of tuyère blocks, means 55 provided between said tuyère blocks defining inlet passages for draft air, a source of air supply, and a plurality of automatically operable dampers, one damper being pivotally mounted on each of said tuyère blocks, for controlling the 60 flow of air in the passage associated therewith, said dampers being disposed substantially longitudinally in respect to the direction of air flow in said passages, and being so arranged that one side of each is subjected to the pressure of the 65 air in its passage and the other side to the pressure of the air at said source of supply, whereby when said differential pressures exceed a predetermined value said dampers move to closed position.
